United States Patent Office

Des. 195,502
Patented June 25, 1963

195,502

PANELLING MATERIAL OR THE LIKE

Colman Zola, 58 Tamarack Way, Pleasantville, N.Y.

Filed May 7, 1962, Ser. No. 69,998

Term of patent 3½ years

(Cl. D13—1)

FIG. 1

FIG. 2

FIG. 1 is a front view of a paneling material showing my new design; it is to be understood that the design is repeated both horizontally and vertically the length and width of the paneling material; and

FIG. 2 is a perspective view of the same.

The undisclosed side of the paneling material is substantially plain.

I claim:

The ornamental design for a paneling material or the like, as shown and described.
